UNITED STATES PATENT OFFICE.

NAT CARRUTH, OF LAGRANGE, GEORGIA, ASSIGNOR TO HILLSIDE COTTON MILLS, OF LAGRANGE, GEORGIA, A CORPORATION OF GEORGIA.

LAUNDRY BASKET.

Application filed February 26, 1926. Serial No. 90,884.

This invention relates to improvements in laundry baskets of that type which are used to carry large quantities of soiled clothing or like articles from place to place in a laundry.

5 The principal object of the invention is to generally improve baskets of the type specified and render them strong and durable and capable of being subjected to hard usage without injury by reinforcing the 10 structure thereof at all points where necessary through the medium of a comparatively simple and effective continuous formation of the uprights of the frame of the basket with diagonally arranged intersecting cross braces 15 disposed in the bottom framework of the basket.

A further object of the invention is to provide a basket of the class specified having a frame preferably made up of parts 20 which may be readily associated and applied to a base and so arranged as to equally distribute the strain over the entire basket structure in such manner as to prevent breaking down or bending of the frame components and at the same time produce a more 25 effective base organization, and wherein, also, the fabric or canvas pouch or receptacle associated with the frame will be shielded against undue wear from the exterior of 30 the basket.

With the foregoing and other objects and advantages in view, the invention consists in the construction and arrangement of the several parts which will be more fully hereinafter described and claimed.

In the drawings:

Fig. 1 is a perspective view of a laundry basket embodying the features of the invention and showing the fabric or canvas pouch broken away in part to more clearly illustrate the frame organization.

Fig. 2 is a bottom plan view of the basket with the fabric or canvas pouch removed.

Fig. 3 is a top plan view of a modified 45 form of the basket with the fabric or canvas pouch removed.

Fig. 4 is a longitudinal vertical section on the line 4—4, Fig. 3, showing parts of the base structure broken away and also particularly illustrating end rollers and a central swivel caster.

Fig. 5 is a top plan view of a further

modified form of the basket with the fabric or canvas pouch removed.

Fig. 6 is a side elevation of the form of 55 basket shown by Fig. 5.

The frame of the basket is composed of runners 5 in predetermined spaced relation and connected by transverse tie members or slats 6 and diagonally arranged brace rods 7 continuing at the outer edge portions of the runners into right-angular uprights 8 secured over a continuous rim rod 9. The top portions of the runners 5 are regularly formed with seat recesses 10 extending thereacross in reverse diagonal directions in accordance with the brace rods 7 which are fitted therein. The brace rods 7 extend under the tie members or slats 6, and over the runners 5, and the ends of said tie members or slats 6 metal straps 11 are secured and continued around the ends of the runners and partway under the lower side of the latter, to form wear guards as at 12. At the points of intersection of the reversely arranged diagonal brace rods 7 a portion of the said rods, or the uppermost ones, are slightly bent or struck upwardly to form seats 13 to partially embrace the intersecting rods 7 below the same and produce a close 80 assemblage of the brace rods. The brace rods 7 form a part of the base structure of the frame of the improved basket, the complete base structure including these rods, the runners 5 and the cross members or slats 6. 85

The runners 5 and the tie members or slats 6 are preferably formed of wood, but other material may be used if found necessary and the metal straps 11 are firmly secured to the runners and where they extend over the ends of the cross tie members or slats 6, said metal straps are struck upwardly as at 14, to provide an additional reinforcing means for the said members or slats 6, with obvious advantages to the general structure of the base of the frame of the basket. In the form of the basket shown by Figs. 1 and 2 the frame structure, or the rods 7 continued into the uprights 8 as well as the rim rod 9, are of comparatively small diameter but may be modified as desired, and furthermore, the rim rod 9 is shown as circular in cross section but this rod may be oval or consist of a flat band as the shape thereof does

not affect the function of this rod as a rim means. Also in the form of the basket shown by Figs. 1 and 2 there are but two runners and the brace rods 7 are confined to 5 two pairs which centrally intersect.

The pouch 15, partially shown by Fig. 1, is of suitable fabric, preferably canvas, and is disposed inside of the uprights 8 with the bottom 16 thereof resting upon the base 10 organization of the frame of the basket. The upper edge of the pouch 15 is turned over and secured to the rim rod 9, as at 17, and the outer side of the said pouch is also connected to the uprights 8 by vertical strips 15 18 applied over the said uprights and secured against the outer side of the pouch. The pouch is also provided at each end with a handle or grip means 19, to facilitate dragging movement of the basket.

20 In Figs. 3 and 4 a modification of the basket is shown and consists in adding a central runner 20 having a metal strap 21 extending thereover and continuing around and under the ends of the runner in the same 25 manner as shown by Fig. 1, the remaining parts of the frame structure in this form of the basket being mainly similar to that illustrated in Figs. 1 and 2 and having like reference characters applied thereto. In the 30 form of the frame structure shown by Figs. 3 and 4 the cross tie members or slats 6 are increased in number, there being four of these cross tie members or slats shown by Figs. 1 and 2 and five illustrated by Figs. 35 3 and 4. Moreover, the metal straps 11 on the outer side runners 5 are narrower than the similar straps shown by Figs. 1 and 2 and the cross tie members or slats 6 rest on top of all of the metal straps 11 and 21 and are 40 not crossed or partially enclosed by any portion of the straps as in the structure shown by Figs. 1 and 2. The top rim 9^a shown by Figs. 3 and 4 is in the form of a flat band. The ends of the runner 20 are recessed or 45 shouldered as at 22, to receive roller brackets 23 provided with rollers 24 of any suitable form to assist in the movement or propulsion of the basket, and at the center of the outer runners 5, rollers 25 are mounted to facilitate 50 turning or swinging the basket during its movement. The brackets 23 with their rollers 24 and the rollers 25 may be of any suitable form and applied in any advantageous manner to the runners, the swivel rollers 25 55 having trunnions 26 seated in recesses 27, which are covered by bearing plates 28, as clearly shown by Fig. 4. In the slightly modified form of the basket as shown by Figs. 3 and 4 the diagonally arranged rods 60 7 continuing into the uprights 8 are of the same number as shown by Figs. 1 and 2 and their dimensions may be modified at will.

In the further modified form of the basket as shown by Figs. 5 and 6 there are two outer 65 runners 29 and two intermediate runners 30

and 31, all of which have metal strips secured against the upper sides thereof and continuing over the ends and under the said runners for a short distance similarly to the structure shown by Figs. 1 to 4, inclusive. The basket shown by Figs. 5 and 6 is of materially greater capacity than that shown by Figs. 1 and 2 and the runners or skids are correspondingly increased to sustain the additional load that will be imposed upon the base 70 structure of the frame. It will also be seen that the diagonally arranged brace rods 33 in the structure shown by Figs. 5 and 6 are increased in number and are continued into angular uprights 34 and attached at 75 their upper terminals to a rim rod 35. The cross tie members or slats 36 are the same in number as in Figs. 3 and 4, the additional strength of the base structure in the modified form shown by Figs. 5 and 6 being obtained 80 through the additional runner or skid and the increase in the number of diagonally arranged brace rods, which, as will be seen, have a correspondingly greater number of angles of intersection and thereby also increase the solidity of the base structure of the frame. The end rollers or casters 37 are secured to the end cross tie members or slats 36 and in this instance, also, are side rollers 38 in all respects similar to those disclosed by Figs. 3 and 4. It is only necessary to use two end rollers or casters 24 and 37, or one at each end in the center, the casters or rollers 24, with their brackets 23 being secured to the central runner or skid 20 in Figs. 3 and 4 and, as just explained, to the centers of the end cross tie members or slats 36 in the form of the basket shown by Figs. 5 and 6. It will be understood that the same 90 form of pouch 15 will be applied to the modified forms of the basket as illustrated by Figs. 3 to 6, inclusive, as is shown in connection with the form of the basket illustrated by Figs. 1 and 2, it being only necessary to increase the dimensions of the pouch. 95

It will be seen in all of the forms of the basket hereinbefore illustrated that the brace rods 7 in Figs. 1 to 4, inclusive, and 33 in Figs. 5 and 6, have the uprights continuing therefrom constructed in U-shaped form, or each unit comprising a brace rod and two uprights is applied to the runners or skids and fixed, to thereby produce a properly positioned brace rod and two uprights without requiring separate attachment of the brace rods and uprights. This feature is of material advantage in the assemblage of these brace rods and uprights and ensures a certainty in positioning the same in accordance with a predetermined distance of separation which may be varied proportionately to the variation in dimensions of the basket to be produced. By means of the continuous structure of each brace rod with two uprights, the basket is materially 100 105 110 115 120 125 130

- strengthened and reinforced, and the reinforcing function of the brace rods is also increased by the diagonal intersection of the said brace rods, this latter feature further 5 providing a more stable and reliable base support for the fabric pouch secured within the frame, and the pulling or pushing strain exerted on the improved basket is more evenly distributed.
- 10 The baskets herein disclosed are of such shape that they may be readily nested when not in use, or for storage or transportation, and moreover, reinforcing or strengthening devices may be applied at such points as 15 may be found necessary, to give the baskets greater rigidity, particularly baskets of large dimensions.
- What is claimed as new is:
1. A laundry basket of the class specified, 20 having a base structure composed of longitudinal and transverse connecting members comprising longitudinal runners in parallel relation and transverse tie members secured at their opposite extremities to the upper 25 sides of the runners, a plurality of U-shaped units arranged in pairs and having horizontal members diagonally crossing in the base structure below the said tie members, the runners having metal straps secured over 30 the upper surfaces thereof and continued around the ends and partially over the lower sides of the opposite extremities of the said runners, said straps also extending over the horizontal members of the U-shaped 35 units crossing the runners, roller devices applied to the base to facilitate movement
- thereof, a rim surrounding the top of the basket and having the upper ends of the uprights secured thereto, and a pouch associated with and connected to the uprights 40 and rim and having the bottom thereof loosely engaging the base structure.
2. A laundry basket of the class specified, 45 having a base structure composed of longitudinally disposed, parallel runners and transverse connecting members terminally bearing on the upper surfaces of the runners, metal straps extending the full length over the upper sides of the runners and over the opposite ends of the latter and partially 50 over the undersides of the said runners, the straps being bent at intervals over and embracing the ends of the transverse connecting members, intersecting, diagonally arranged pairs of horizontally disposed rods 55 under the connecting members and extending over the upper edges of the runners beneath the straps, the longitudinal members being continued into vertical, parallel uprights along the outer side edge portions of 60 the runners to form a skeleton frame for the basket, the uprights providing reinforcing means for the basket structure, a rim surrounding the top of the basket and connected to the upper ends of the uprights, 65 and a pouch associated with and connected to the uprights and rim and having the bottom thereof loosely engaging the base structure.

In testimony whereof I have hereunto set 70 my hand.

NAT CARRUTH.
